UNITED STATES PATENT OFFICE

GEORGE E. SMITH, OF PARK HILLS, KENTUCKY, ASSIGNOR TO THE UNITED STATES ELECTRICAL TOOL COMPANY, OF CINCINNATI, OHIO, A CORPORATION OF OHIO

TOOL DRIVING APPARATUS

Application filed July 30, 1928. Serial No. 296,200.

This invention relates to tool driving apparatus of the portable type and is particularly directed to a combination power driven and manually operated tool driving device incorporating safety features. The use of power for actuating a tool such as a wrench or screw driver is of extreme advantage especially concerning the item of speed in primarily drawing up the bolt, nut or screw to the part to be fastened.

It is necessary in the use of power in driving certain tools to automatically discontinue the drive after a certain pressure or force is exerted on the nut or bolt, otherwise unlimited power would strip the threads. Where there is a wide range in the size of the tool used with the device, it is of considerable difficulty to determine and arrange for an automatic drive discontinuation since the size of the bolt or nut, the coarseness of the thread, the length thereof and the tightening necessary, vary greatly in given pieces of work.

It has, therefore, been found extremely difficult to design a power driven tool which would draw the parts up to the proper degree.

It is an object of this invention to provide a power driven portable tool which will quickly draw up the nut, bolt, screw, etc., and in which the drive will be automatically discontinued as the same pressure or degree of force is exerted on the work in all instances. That is to say, this invention contemplates the provision of power means for quickly drawing up a bolt or nut but rendered incapable of exerting a tightening force thereon.

It is a further object to provide in combination with the controlled power drive a device for connecting the tool for a convenient manual actuation thereof.

It is another object to provide a ratchet operated mechanism for use in the hand actuating phases of the operation of the device.

Still another object is to provide a driven clutch element carrying the tool, which may be alternately used either for a steady power drive or which may be used for a hand drive with a ratchet movement incorporated there-

in, and to provide that the changes in mode of drive are quickly and conveniently made by shifting the driven tool carrying element.

Still another object is to provide a clutch controlled power driven mechanism for a device of this nature which is reversible as to the direction of the drive.

Another object is to provide an improved attaching means for the various tools used in combination with the device.

Another object is to provide a novel arrangement for a transmitted drive reversal.

Other objects and further advantages will be more fully set forth in a description of the accompanying drawings forming a part of this specification, in which:

Figure 1 is a side elevation of a tool driving apparatus incorporating the present improvement.

Figure 2 is a top plan view of Figure 1.

Figure 3 is a sectional view taken on line 3—3, Figure 1, detailing the clutch and the means for converting the drive from power to manual operation.

Figure 4 is a sectional view taken on line 4—4, Figure 3, detailing the power transmission to the driving clutch member.

Figure 5 is a sectional view taken on line 5—5, Figure 3, showing the means for attaching the tool within the desired spindle or driven clutch member.

Figure 6 is a sectional view taken on line 6—6, Figure 3, illustrating the arrangement of the teeth on the stock of the device and relative position of the companion teeth of the clutch element thereto.

Figure 7 is a view taken similar to Figure 3, showing one side of the drive and illustrating the driven clutch member or tool holding spindle in connection for a power drive.

Referring to the general views of the drawings, the various casings of the device are secured together in T-shaped assemblage. The motor and its casing indicated at 1, and the handle 2 extending from the motor casing and containing the starting switch, constitute the shank of the T-shaped casing arrangement. The electrical connection for the motor extends from the end of the handle and is indicated at 3. As shown in Figure 3, the

drive from the motor extends from the shank to the intersection of the tool stock or head 4 and the shank and then to either end of the head.

5 The motor shaft, indicated at 5 (see Fig. 4) has its driving end journalled in a ball bearing 5^a in the motor casing end wall. The shaft protrudes from the motor casing into a casing 6 forming the head of the T or the tool stock for housing various clutch and transmission elements making up a two direction drive. A gear 7 is secured on the outer end of the shaft 5 and is in mesh with a gear 8 keyed to a drive shaft 9 also journalled in the 10 motor casing end wall at one end as at 10 and in the casing 6 at the other end in a ball bearing 11.

The shaft 9 has a worm 12 formed intermediate thereof in mesh with a worm gear 13 20 rotatably journalled axially of the casing 6 (see Figure 3). The casing 6, for the purpose of assemblage, is made in two sections secured together by screws 14, the assembled casing 6 being secured to the motor casing by 25 means of screws 6^a traversing the base flange 6^b of the casing.

The worm gear 13 is keyed to a double faced clutch element 15, this element being mounted at either side of the worm gear in a pair of 30 sleeves 16—16 rotatably journalled within the bore of the drive housing casing 6. The driving clutch element presents a pair of diametrically disposed teeth at each end thereof.

35 Tool holding spindles or driven clutch members 17 are rotatably translatable mounted in the respective end regions of the stock casing 6 providing a two direction drive and alternately engageable with the driving clutch element 15. Inasmuch as the respective driven members or tool holding spindles for each direction of drive are the same in either instance, the description will be confined to one side. The tool holding spindle 40 provides a shank portion 18 and a head 19, the shank being slidably mounted in the bore of the sleeve 16 relative to the respective driving teeth of the clutch element 15, and the headed end 19 being slidably mounted in the bore 45 of the casing 6.

50 Teeth 20 companion to teeth 21 of the driving clutch element are formed on the opposing end of the tool holding spindle. The engaging edges of the registering teeth are sufficiently inclined so as to prevent an absolute rotative interlock of the clutch teeth and therefore are automatically disengaged, regardless of the pressure exerted to hold them in engagement, when the driving force needed 55 has reached a certain degree.

60 A cap 22 is screwed into the end of the casing 6 and has a series of inwardly disposed teeth 23 formed thereon. These teeth are circumferentially disposed and are adapted 65 for registry with companion teeth 24 formed

on the outer face of the headed end of the tool holding spindle 17.

The member 17 is normally held out of engagement with the motor driven clutch element by means of a coil spring 25 under compression between the outer end of the sleeve 16 and the inner face of the head 19. The spring thus holds the tool holding spindle teeth 24 in engagement with the teeth 23 formed as a part of the casing.

70 The registering teeth or companion teeth 23, 24, in each instance provide a straight, sharp tooth edge engagement for a positive rotative engagement in one direction and an inclined surface in the instance of the teeth 23 for disengagement of the teeth in the opposing direction.

75 The tool holding spindle 17 has a square bore extending therethrough indicated at 27, providing a socket for the tool shank 28 carrying the desired tool 29, indicated as a socket wrench in this instance. The cap 22 has a central bore providing a clearance for the rotating shank passing therethrough. The shank is limited as to insertion into the socket by engagement with a cross pin 30 diametrically secured in the member 17 toward the inner end thereof.

80 The shank is held or maintained in place within the socket by means of a detent 31 disposed within the shank and engaging a radially disposed orifice formed in the tool holder and indicated at 32. The various tools may or may not be an integral part of the shank.

85 The operation of the device is as follows:

90 When the switch control for the motor is thrown, the worm gear and driving clutch element are set in motion presenting alternately engageable driving clutch faces. The tool is engaged with the head of the screw to be drawn up or with a nut, as the case may be, and the entire device is forced downwardly (see Figure 7), this action translating the respective tool holding spindle and engaging the teeth thereof with the teeth of the driving clutch element.

95 When the rotative drawing up process has proceeded to the point where the resistance against rotation of the spindle is great enough to cause the inclined teeth edges to become disengaged, the power drive will then be discontinued and any amount of downward force applied will be ineffective to tighten the respective screw or nut. The translatable clutch element or spindle is then released from its depressed position and engages the teeth formed in the cap as a part of the body of the device.

100 The operator then rotates the entire device on a center coincident with the center of the casing 6 using the shank of the T-shaped casing as the lever, and a manual tightening force is exerted on the screw or bolt.

105 Due to the fact that the engagement of the

teeth at this time on straight, sharp tooth edges, this manual tightening force may be exerted to completely tighten the parts until it is deemed that the parts are sufficiently 5 tight. This manual tightening may be accomplished by using the ratchet formed by the spring pressed engagement of the teeth 23, 24, the teeth 23 being of saw-tooth formation for disengagement from the opposing 10 teeth upon attempted reverse rotation.

By virtue of this mechanism, a power drawing up and a manual tightening is possible, with the change from one direction drive to another very conveniently made by turning 15 the device over. The discontinuing of the power drive is rendered automatic to safeguard the screw or parts from breaking under power tightening force.

The views of the drawings show the device 20 in position for loosening a screw. To reverse the action or tighten the screw the operator turns the device over, that is to say, rotates it on the axis of the motor casing portion. The result of this is that the drive 25 line through the tool stock is upset end for end and with a one direction motor, a drive reversal is possible.

Having described my invention, I claim:

A tool driving device of the class described 30 comprising a T-shaped casing, a power device located in the shank of said T-shaped casing, a driven element connected to said power device and rotatably mounted in axial alignment with and within the head of the T- 35 shaped casing, said driven element having clutch teeth disposed toward the respective ends of the head of said T-shaped casing, tool spindles reciprocably mounted in the respective ends of said head and each including 40 clutch teeth engageable with the respectively adjacent clutch teeth of said driven element, said spindles each having ratchet teeth at their outer ends, said casing including ratchet teeth formed inwardly at the ends of said 45 head thereof for engagement with the respectively adjacent ratchet teeth of said driven element, springs for normally maintaining said spindles out of engagement with the driven element and in ratchet engagement, 50 and a handle extended from the shank of the T-shaped casing for oscillating the said casing on the axis of the head for manipulation of a particular ratchet for manually operating the particular tool whereby the tools may 55 be manually operated in normal spring urged position or power actuated by depression of the spindles into engagement with the driven element.

In witness whereof, I hereunto subscribe 60 my name.

GEORGE E. SMITH.
